UNITED STATES PATENT OFFICE.

HERBERT P. ELLERBECK, OF CARLTON, MINNESOTA.

RAIL-CHAIR.

No. 895,246.

Specification of Letters Patent.

Patented Aug. 4, 1908.

Application filed February 17, 1908. Serial No. 416,248.

To all whom it may concern:

Be it known that I, HERBERT P. ELLERBECK, a subject of the King of Great Britain, residing at Carlton, in the county of Carlton and State of Minnesota, have invented certain new and useful Improvements in Rail-Chairs; and I do hereby declare the following to be a full, clear, and exact description of the invention, such as will enable others skilled in the art to which it appertains to make and use the same.

My invention relates to rail chairs for railway rails and has for its object the provision of means for preventing the rail from creeping longitudinally.

With this and other objects in view, it consists of the constructions, combinations and arrangements of parts hereinafter described and claimed.

In the drawings, Figure 1, is a perspective view of the preferred form of my invention. Fig. 2, is a similar view of the lower plate thereof. Fig. 3, is a similar view of the upper plate thereof. Fig. 4, is a fragmentary perspective view of a modified form of my invention. Fig. 5, is a plan view of said invention showing the plates in partly retracted position. Fig. 6, is a vertical transverse section on the line A—B of Fig. 1, showing the rail mounted on the chair, and a supporting cross tie. Fig. 7, is a vertical transverse view of said invention approximately similar to Fig. 1, but showing the upper and lower plates in retracted position, and omitting the tie.

In the drawings, 1, is a base plate having depending flanges or teeth 1^a adapted to bite into the cross tie 2 and prevent horizontal movement of said plate. Said plate has formed thereon or secured thereto upon the upper face thereof, a shoulder 1^b upon which is formed or secured a shoulder 1^c which shoulder 1^c preferably has formed thereon an overhanging lip 1^d adapted to overhang one of the flanges 3^a of a railway rail 3. Extending into said shoulder 1^c are one or more keys or pins 4 having an exposed edge as 4^a adapted to bite into said flange. A spike passage 1^e is formed in said plate preferably at one side of said shoulders 1^b and 1^c and a second spike passage 1^b is formed in said plate preferably near the opposite end thereof and diagonally opposite to the first said spike passage. In said drawings, 5 is an upper plate indented or cut away at one corner as at 5^a to receive the shoulder 1^b of said lower

plate, upon which lower plate said upper plate is adapted to be mounted. Formed on or secured to said upper plate is a shoulder 5^b preferably diagonally opposite to said shoulder 1^c. Said shoulder 5^b is preferably provided with an overhanging tongue 5^c adapted to overhang the opposite flange of said rail. Said upper plate is provided with spike passages 5^d adapted in operative position to approximately register with the spike passages in said lower plate. One or more pins or keys 5^e extend into said shoulder 5^b, said keys having exposed edges, as 5^f, adapted to bite into said opposite flange of said rail. Spikes 6 extend through said spike passages into the tie 2. If desired, the overhanging tongues on said shoulders 1^c and 5^b, as is indicated in Fig. 4, may be omitted.

In operation said plate 1 is slipped under the flange of the rail from one side and the plate 5 is slipped under said flange from the opposite side and above said plate 1, the keys in said shoulders being first preferably placed in position in the shoulders, and coming into contact with the edges of the rail flanges as said plates are slipped under the rail. The spike passages of the upper plate are not at such time wholly in registration with the corresponding passages of the lower plates, and the keys do not yet bite into the rail flanges. Upon inserting the points of the spikes and driving the spikes home, the plates are drawn farther together by the wedging operation of the spikes in forcing their passage through the upper and lower spike passages, and the keys may thus be caused to bite into the rail flanges, thus preventing creeping of the rails. The weight of passing trains will force the flanges 1^a down into the tie. If the overhanging tongues on said shoulders are omitted, as may be, the spike passages are so placed, as shown in Fig. 5, that the lips of the spike heads will overhang the flanges of the rails.

It is obvious that said invention may be further modified within the scope of certain of my claims, and especially so with respect to the form of said keys and with respect to their position in said shoulders.

What I claim is:

1. In a rail chair, the combination of two plates, one superposed upon the other, and both adapted to extend beneath the flange of a railway rail, one of said plates being provided with a shoulder adapted to extend upwardly at one side of said flange and the

other of said plates being provided with a shoulder adapted to extend upwardly at the other side of said flange, keys extending into said shoulders and adapted in operative position to bite into said flange, and means adapted to secure said plates to a railway cross tie.

2. In a railway chair, the combination of two overlapping plates, one of said plates being provided with a shoulder adapted to engage the flange of a railway rail at one side thereof, the other of said plates being provided with a shoulder adapted to engage the

opposite flange of a railway rail, said shoulders being provided with tongues adapted to overlap said flanges, keys extending into said shoulders and having exposed edges adapted to bite into said flanges, and means for securing said plates to an underlying railway cross tie.

In testimony whereof I hereunto affix my signature, in presence of two witnesses.

HERBERT P. ELLERBECK.
